UNITED STATES PATENT OFFICE.

EUGENE COOK, OF KALAMAZOO, MICHIGAN.

CATTLE-GUARD.

SPECIFICATION forming part of Letters Patent No. 723,833, dated March 31, 1903.

Application filed February 15, 1902. Serial No. 94,279. (No model.)

To all whom it may concern.

Be it known that I, EUGENE COOK, a citizen of the United States, residing at the city of Kalamazoo, in the county of Kalamazoo and State of Michigan, have invented certain new and useful Improvements in Cattle-Guards, of which the following is a specification.

This invention relates to improvements in cattle-guards.

10 The objects of this invention are, first, to provide a cheap and efficient means of retaining parallel wooden bars intended for use in cattle-guards in position; second, to provide such a structure adapted for use in connection 15 with means for supporting serrated protecting bars or rails.

Further minor objects will definitely appear from the detailed description to follow.

I accomplish the objects of my invention 20 by the devices and means described in this specification.

The invention is clearly defined, and pointed out in the claims.

A structure embodying the features of my 25 invention is clearly illustrated in the accompanying drawings, forming a part of this specification, in which—

Figure 1 is a plan view of a cattle-guard embodying the features of my invention. 30 Fig. 2 is a side elevation of the same. Fig. 3 is an enlarged detail transverse sectional view taken on a line corresponding to lines 3 3 of Figs. 1 and 2. Fig. 4 is a detail transverse sectional view taken on a line corresponding to lines 4 4 of Figs. 1 and 2.

In the drawings all of the sectional views are taken looking in the direction of the little arrows at the ends of the section-lines, and similar letters of reference refer to similar parts throughout the several views.

Referring to the lettered parts of the drawings, A represents longitudinal wooden rails, making up the main body of my improved cattle-guard. These are narrowed to an edge 45 at the top and widened into a comparatively wide base at the bottom and are adapted to stand on such base with the sharp edges projecting upwardly. These rails are supported on cross-pieces B D. The cross-pieces B are 50 provided with upwardly-projecting lugs B', arranged in pairs. The pairs of lugs are separated a distance equal to the space occupied

by two of the rails and are adapted to engage the opposite sides of pairs of adjacent rails. A wedge-block B'', adapted to draw down between the adjacent pairs of rails and in connection with the lugs B' clamp the same in position, is secured to the cross-piece B by a bolt C. It is preferred to form the parts in such a manner that the wedge-pieces B'' will 55 not quite come in contact with the cross-piece B, so that the bolt C can be tightened in the event of the shrinking of the wood.

To make the guard particularly effective, I place serrated metal rails A' A' on top of the 60 wood rails A at one end, the upper portions of the wood rails being cut away to accommodate the same, as clearly appears in Figs. 2 and 4.

Beneath the cut-away portions of rails A 65 cross-pieces D are substituted for cross-pieces B, and above these cross-pieces cross-bars E are laid on top of the rails. These cross-bars have pairs of oppositely-facing shoulders, against which the serrated metal rails A' A' 70 are secured by clip-pieces E', which are secured to the cross-bars E by bolts a. When assembled in this way, they are clamped on top of the rails A by means of bolts e, which are passed through the cross-pieces E and D. 75

The cross-pieces D are provided with seats for the rails, and the rails are clamped into these seats by means of the cross-bars E and bolts e described. The cross-bars D are provided for use in connection with the serrated 80 metal-rail construction as being slightly more economical, although, if desired, the cross-bars B may be used in this connection.

This makes a guard which is very effective and cheap to manufacture, because the 85 wooden rails A are much less expensive than metal. When the serrated metal rails A' are used, the guard has all the advantages of metal rails, as for a distance at the outer end or the highway end of the guard these wood rails 90 are protected or armed on their upper edge with the serrated metal rails A'.

Having thus described my invention, what I claim as new, and desire to secure by Letters Patent, is—

1. In a cattle-guard, the combination of the rails A, wide at the base and narrow at the top; a cross-piece B with lugs B' projecting upwardly therefrom against the opposite sides

of pairs of adjacent rails; and a wedge-shaped piece B" inserted and clamped between the rails of each pair and clamped to the cross-bar B below, coacting for the purpose specified.

2. The combination of rails A, wide at the bottom and narrow at the top; cross-bars with lugs thereon, spaced to engage the opposite sides of pairs of adjacent rails; and wedge-

shaped pieces with means of securing the same between the rails of each, as specified.

In witness whereof I have hereunto set my hand and seal in the presence of two witnesses.

EUGENE COOK. [L.S.]
